FIG. 1

FIG. 2

FIG. 3

UNITED STATES PATENT OFFICE

LOUIS H. VERONNEAU, OF MONTREAL, QUEBEC, CANADA

RADIATOR

Application filed August 19, 1927. Serial No. 214,181.

This invention relates to new and useful improvements in radiators and, particularly, to radiators provided with individual electric heating elements, and the object of the invention is to provide a radiator with means attached thereto for feeding water thereto in such a manner that the current consumption of the heating element will remain practically constant.

Another object is to provide a radiator having a feed water tank attached thereto to keep the water within the radiator at a constant level.

In my invention I provide a radiator of the usual type, provided with a heating element connected to a source of electrical current supply. Apertures are formed in the upper portion of the radiator to position a feed water tank, the outlet from which is a depending pipe which projects into the radiator. The feed water tank is provided with a plug fitting into the inlet opening. The radiator feed water tank outlet is closed by the water in the radiator and as the water falls below said outlet, the water from the tank tends to keep the water in the radiator at constant level.

In the drawings which illustrate one form of my invention:—

Figure 1 is a perspective view of a radiator with my improved water feed tank attached thereto.

Figure 2 is a sectional side elevation of the radiator shown in Figure 1.

Figure 3 is an enlarged detail sectional elevation of the heating element.

Referring more particularly to the drawings, 11 designates a radiator having a plurality of horizontal water passages 12, communicating with vertical passages 13 to form a circulating means for the water within the radiator. The radiator may be provided with stands 14, to hold the lowermost portion of the radiator clear of the floor and allow the air to pass thereunder. Positioned near the bottom of the radiator is the threaded aperture 15, adapted to receive a heating element designated as a whole by the numeral 16. This heating element may consist of a threaded plug 17 having hollow perforated sleeves

18 and 19 projecting into the radiator. Mounted within the sleeves and spaced from the inner walls thereof are the carbon or carbon composite rods 20 and 21 which may be held in place by means of the rods 22 and 23 insulated from the casing by means of the bushings 24 and 25. The rods are connected to a switch 26 of the three-way type, which regulates the flow of current to the heating element. No detail of the switch is shown as any of the standard types well known in this art may be used for this purpose. A common return wire is used and is connected between the switch and the sleeve in any suitable manner, such as by means of the terminal stud 27. The switch is connected by means of the wire to a source of current supply (not shown) by means of the plug and socket connection designated 28. A gland 29 may be bolted or otherwise secured to the sleeve and insulated therefrom by means of the washer 30 and suitable packing rings 31 may be fitted in the gland and pressed against the insulated cable 32 by means of the flanged bushing 33, pressure being brought to bear on said bushing 33 by means of the nut 34, the threaded portion of which engages with the threaded wall of the gland. The gland structure is provided to seal the radiator and prevent water from flowing through the apertures formed for the wiring of the heating elements. It will be noticed that one of the carbon rods is made smaller than the other and this is provided so that the current consumption of the heating elements may be altered by means of the switch, the smaller heating element being designed to consume considerably less current than the larger. Formed in the top of the radiator and at each side thereof, are the apertures 35 and 36, each adapted to receive one of the projections 36^a and 37, of the feed water tank 38, which project downwardly therefrom. Positioned substantially midway between said projections is the threaded aperture 39 adapted to receive the threaded plug 40. Depending from one of said projections in the feed water tank is the pipe 41, which forms a source of communication between the interior of the tank and the interior of the radiator. A

small aperture 42 may be formed in the upper part of the radiator to form a relief vent therefor.

In the drawings I have shown one type of radiator to which my improvements may be attached, but it will be readily understood that many modifications may be made in the general construction of the radiator without departing from the spirit of the invention.

In operation water is fed into the radiator through the aperture at the top thereof and the tank is filled with water through the aperture provided for that purpose and preferably situated on the side of the tank having the projections which fit into the apertures in the radiator. The tank is closed by means of the plug and is then placed on the top of the radiator with the projections fitting into the apertures in the top of the radiator. The feed pipe from the tank is sealed by means of the water in the radiator. Current is then supplied to the heating element of the larger capacity and when the water within the radiator has reached the desired temperature, the larger heating element is cut out and the smaller element used, as it is well known that less heat is required to keep the water at said desired temperature. The power expended in the circuit is affected by the temperature of the water and the resistance lessened so that it requires very little power to keep the water near boiling point. There is, of necessity, a certain amount of evaporation of the water within the radiator and when the water falls below the level of the discharge end of the tube depending from the tank, the water from the tank flows into the radiator and tends to keep the water therein at constant level. It will also be noticed that the feed water from the tank will be of approximately the same temperature as the water in the radiator, so that the feed water will not affect the current consumption of the heating elements.

The device is very simple and inexpensive to manufacture and provides a highly efficient heating device for rooms, factories and the like. It also provides a hot water heating system which is easily installed, and which is very economical in operation.

Having thus described my invention, what I claim is:—

A radiator comprising a casing presenting a top wall, having a relatively large opening formed therein near each end and a relatively small vent opening formed therein intermediate said large openings, a feed water tank having its bottom wall directly supported on the top wall of said casing, the intermediate portions of the engaging walls of the casing and tank being spaced apart to place the vent opening of the casing in communication with the atmosphere, projections depending from the bottom wall of said tank and fitting in the relatively large openings formed in the

top wall of said casing, one of said projections being provided with a pipe extension depending into said casing and affording the sole means of communication between the casing and the tank, said pipe extension functioning as a delivery pipe supplying water from the tank to the casing and being arranged to be sealed by the water in the casing when said water reaches a predetermined level.

In witness whereof, I have hereunto set my hand.

LOUIS H. VERONNEAU.
